UNITED STATES PATENT OFFICE

WILLIAM M. ADRIAN, OF CHICAGO, ILLINOIS

DESIGN FOR A LAMP BASE

Application filed July 15, 1931. Serial No. 40,550. Term of patent 3½ years.

To all whom it may concern:

Be it known that I, WILLIAM M. ADRIAN, a citizen of the United States, residing at Chicago, in the county of Cook and State of Illinois, have invented a new, original, and ornamental Design for Lamp Bases, of which the following is a specification, reference being had to the accompanying drawings, as forming part thereof.

Figure 1 is a top plan view of a lamp base, showing my new design, and Figure 2 is a side elevation of the same, it being understood that the opposite side of the base is substantially identical.

I claim:

The ornamental design for a lamp base, as shown and described.

WILLIAM M. ADRIAN.
